UNITED STATES PATENT OFFICE.

EMIL C. RAUSCHENBERG, OF WHEELING, WEST VIRGINIA, ASSIGNEE TO WHEELING MOLD & FOUNDRY CO., OF WHEELING, WEST VIRGINIA.

CAST-METAL ANNEALING BOX.

Application filed December 28, 1922. Serial No. 609,416.

To all whom it may concern:

Be it known that I, EMIL C. RAUSCHENBERG, a citizen of the United States, residing at Wheeling, in the county of Ohio and State of West Virginia, have invented certain new and useful Improvements in Cast-Metal Annealing Boxes, of which the following is a specification, reference being had therein to the accompanying drawing.

10 This invention relates to improvements in cast metal annealing boxes and it pertains to a metal box constructed for enclosing sheet metal plates to be annealed.

One object of my present invention is to 15 construct the box with an external longitudinally extending strengthening rib.

A further object of my invention is to extend the external rib in a zig-zag line around the outside of the box whereby the box is 20 strengthened.

A further object of my present invention is to provide a box with an external zig-zag rib the depressions of the zig-zag located above the bottom of the box.

25 Further objects of the invention will appear from the following description and disclosure.

Fig. 1 is a combined plan and central horizontal sectional view of my improved box.

30 Fig. 2 is a combined side elevation and central vertical sectional view of my improved box.

Fig. 3 is an end elevation of the improved box.

35 Fig. 4 is a cross sectional view taken through the straight portion of the body of the box.

Fig. 5 is a cross sectional view taken through the center of the corrugation.

40 My cast box is intended to receive a number of plates to be annealed. The construction herein shown involves many features of a co-pending application Serial No. 609,415 filed Dec. 28th, 1922, of mine with an added improvement of an external longitudinally extending strengthening rib.

45 The disclosure of my aforesaid co-pending application will be briefly referred to. The body of the box is provided with corrugations 2 which extend from near its lower edge around the top of the box, the corrugation being deepest at the center of the top of the box 3, for the purpose of giving added strength. As shown these corrugations are separated by straight parts 4

which also add to the strength of the box and prevent it from bending or cracking when subjected to heat action.

50 My present improvement over that shown in the co-pending application relates to an external longitudinal rib 5. This rib extends around the sides and ends of the box and is preferably continuous. At the sides of the box the rib is made zig-zag in shape the upper portions 6 being between the corrugations 2 and the lower portion 7 of the zig-zag being in the center of the corrugations 2. It will be observed that the rib conforms to the shape of the box. That is to say it follows the corrugations 55 as at 8 and the straight portions as at 9.

It will be also observed that the rib has a straight part 10 that extends around the corners 11 of the box and a downward bend 12 at the center of the end of the box, the downward bend being in the center of the end corrugation 13. As shown the rib is 60 preferably below the center of the box, and the downward dips of the zig-zag are preferably adjacent the lower edges of the corrugations 2.

65 I find in practice that this rib very much strengthens the box and adds to its rigidity and life. By means of the zig-zag it more readily accommodates itself to the expansion and contraction of the box, making it a flexible structure while at the same time affording a strengthening rib.

What I desire to secure and protect by Letters Patent is:

1. A cast metal annealing box having an external continuous rib extending around its sides and ends, said rib having a zig-zag shape.

2. A cast metal annealing box having an external continuous rib zig-zag in shape the dips in the zig-zag being below the center line of the box.

3. An annealing box having vertical corrugations extending across the top, and an external continuous rib extending around the sides and ends of the box, said rib extending into the said vertical corrugations.

4. A cast metal annealing box having vertical corrugations and an external continuous rib having zig-zag portions at the said corrugations, said rib extending into the corrugations.

5. A cast metal annealing box having a plurality of vertical corrugations connected

by straight portions, a zig-zag external rib the upward bends of the zig-zag being on the straight portions of the box and the down bends of the zig-zag being in the ⁵ corrugations.

6. A cast metal box having transverse corrugations, the end corrugations spaced

from the ends of the box, a rib zig-zag along the sides of the box, and straight around the corners of the box and a depressed portion at the centers of the ends of the box. ¹⁰

In testimony whereof I hereunto affix my signature.

EMIL C. RAUSCHENBERG.
